UNITED STATES PATENT OFFICE.

GEORGE A. WEIDELY, OF INDIANAPOLIS, INDIANA, ASSIGNOR TO PREMIER MOTOR MFG. CO., OF INDIANAPOLIS, INDIANA, A CORPORATION OF INDIANA.

LUBRICATING AND COOLING SYSTEM FOR ENGINES.

No. 853,288.

Specification of Letters Patent.

Patented May 14, 1907.

Application filed December 24, 1904. Serial No. 238,214.

To all whom it may concern:

Be it known that I, GEORGE A. WEIDELY, a citizen of the United States, residing at Indianapolis, in the county of Marion and State of Indiana, have invented certain new and useful Improvements in Lubricating and Cooling Systems for Engines, of which the following is a specification.

In the use of what is known as the "splash" system of oiling the cranks dip into a pool of oil with sufficient violence to throw the oil to all the parts desired. Such a system works satisfactorily if the pool is of the proper depth, but the quantity of oil delivered by the splash necessarily varies with the variation of depth to which the cranks enter into the pool so that when the pool is too shallow an insufficient amount of oil is splashed and when the pool is too deep too much oil is used. In automobile construction, there is a further difficulty in that the change of level of the roads over which the machine is run necessarily makes a change in the position of the oil pool with relation to the crank shaft. In automobiles having multiple power cylinders arranged parallel with the line of travel, this difficulty becomes very great, so much so that in climbing hills the forward cylinder gets no oil at all, while the rear cylinder gets too much, and this condition is reversed in going down hill.

The object of my invention is to provide means by which all of the advantages of a "splash" system may be retained, and the disadvantages thereof be eliminated.

A further object of my invention is to so construct the parts as to insure a sufficiently low temperature of the oiling chamber so as to prevent charring of the oil.

The accompanying drawings illustrate my invention as applied to a four-cylinder internal combustion engine;

Figure 1 is a side elevation; Fig. 2 a sectional plan on line 2 2 of Fig. 4; Fig. 3 a section on line 3 3 of Fig. 2; Fig. 4 a section on line 4 4 of Fig. 2; Fig. 5 an enlarged vertical section on part of line 4 4 of Fig. 2; Fig. 6 an enlarged horizontal section of the parts shown in Fig. 5; and Fig. 7, a diagrammatic side elevation of an automobile chassis embodying my invention.

In the drawings, 10 indicates a crank shaft provided with a plurality of cranks 11. The

shaft 10 is journaled in suitable bearings 12 formed in the casting 13. The main body of this casting 13 is provided on its under side and across its interior with transverse arms 14 which carry the journal bearings. Each of these cross arms 14 is provided at one side of its bearing 12 with a pair of upright flanges 15 which thus form an oil basin 16, and this basin is connected by a pair of passages 17 with a channel 18 cut in the wearing surface of the bearing 12, and extending out to its ends so as to communicate with the sides of the arms of the cranks 11. Formed in the bottom of the basin 16 near its outer end is an opening 19 which registers with a riser passage 20 formed in the cover 13' which closes the lower end of the casting 13. The several riser passages 20 extend upward from a header passage 31 which extends longitudinally through the cover 13', and communicates at one end with the discharge port 32 of a small rotary pump 33 detachably secured to one end of the cover 13' and connected by a suitable driving train 34 with a shaft 10. The inlet port 35 of the pump 33 lies within an oil reservoir 36 formed in the cover 13', and leading toward this basin is a channel 37 into which channel lead openings 38 formed in the bottom of the cover 13' preferably below each of the bearings 12 provided with an accompanying oil basin 16.

In operation, the oil collects in the reservoir 36 and the depth can be readily seen through the glass 40. At no time will the oil rise enough to permit any one of the cranks 11 to dip into it, but as the engine is operated and its crank shaft rotated, the pump 33 will be driven so as to draw oil from the reservoir 36 and discharge it into the header 31, and forward through the several risers 20 into the several basins 16. The oil flows then from these basins through the passages 17 and out through the connecting channel 18 so as to flow in a steady stream to the sides of the crank arms. The oil then flows outward along these lines, and is thrown in the same manner as oil is thrown in the ordinary splash system so as to fill the chamber formed by the main body 13 and the cover 13', with an oil vapor which thoroughly lubricates all the parts, including the engine pistons. By properly gearing the pump 33 with the crank shaft, the flow of oil to the cranks will at all

- 2
- times be in exact and proper proportion to the speed, and hence to the amount of oil required, and the amount of oil in the reservoir or the level of the engine will have no effect whatever upon the degree of lubrication, and all of the parts needing lubrication will be uniformly lubricated even when the oil in the reservoir reaches its lowest possible level.
- 10 I have found in practice that it is exceedingly desirable that the chamber within which this oiling takes place be kept as cool as possible, and I accomplish the necessary cooling in the following manner: In order to support the construction already described in the main frame of the carriage, I provide the main casting 13 with transverse arms 41 which at their ends are provided with means for attachment to the side bars 42 of the main frame of the carriage 50. These arms 41 are hollow and communicate with the interior of the main body 13. Each arm is then provided with an opening to the interior, the forward arms having inlet openings 43 and the rear arms having outlet openings 44, each of said openings being protected by suitable screenings 45. Extending upwardly and forwardly over the forward openings 43 are shields 46 and extending upwardly and rearwardly from the rear openings 44 are similar shields 47, the arrangement being such that, as the carriage moves forward air will be caught by the forwardly extending shields 46 and forced downwardly through the openings 43 thence through the hollow arms 41 into the interior of body 13 and cover 13', thence rearwardly out through the rear arms 41 and the outlet openings 44. The movement of the air through the casting is facilitated by reason of the suction created by the arrangement of shields 47.

In order to insure a sufficient supply of oil for the crank wrist pins I form opposite each crank a vertical passage 50 which communicates with the header passage 31. In the upper end of each of these passages I insert a short pipe 51 the end of which is bent over and directed toward the path of movement of the crank so that a continuous small stream of oil is directed into said path of movement.

I claim as my invention:

1. The combination, with a crank shaft having a pair of journals one adjacent each crank arm and a cylinder and piston ar-

ranged in alignment with the plane of rotation of each crank, of suitable bearings for said journals, an open oil basin arranged adjacent each journal and having oil passages leading therefrom to the journal and to points adjacent the crank arms, a reservoir to receive surplus oil, and a pump adapted to carry the oil from said reservoir to the oil basins, whereby a sufficient quantity of oil is delivered to the arms of the crank to flow outward along said crank arms and be thrown therefrom upon the rotation of the crank shaft.

2. The combination, with an automobile and an engine carried thereby and consisting in part of a suitable inclosing casing having journal bearings in its interior, and having an air inlet opening at one end and an air outlet opening at the other, together with means for directing air therethrough, of a crank shaft having journals journaled in said bearings, means for supplying a stream of oil to the arms of the crank in such quantity that the oil will be caused by the rotation of the shaft to flow outwardly along the crank arms and be thrown therefrom, the arrangement of the casing and air openings being such as to permit a cooling current of air through the casing during transportation of the structure.

3. In an automobile, the combination with a carriage, of an engine carried thereby and consisting in part of a main hollow body carrying in its interior suitable crank shaft journal bearings, an open oil basin arranged adjacent the ends of the bearing, and a reservoir to receive surplus oil, and said main casing being provided with an air inlet at one end and an air outlet at the other, whereby a current of air will be forced through the casing during transportation of the structure, a pump adapted to carry oil from the reservoir to the oil basins, and a crank shaft journaled in the bearings, all substantially as and for the purpose set forth.

In witness whereof, I, have hereunto set my hand and seal at Indianapolis, Indiana, this 20th day of December, A. D. one thousand nine hundred and four.

GEORGE A. WEIDELY. [L. S.]
